UNITED STATES PATENT OFFICE

97,348

DESIGN FOR A COMBINED BRIDGE AND MECHANISM CASING FOR ICE-CREAM FREEZERS

James J. Gough, Chicago, Ill.

Application August 20, 1935, Serial No. 58,216

Term of patent 7 years

To all whom it may concern:

Be it known that I, James J. Gough, a citizen of the United States, residing at Chicago, in the county of Cook and State of Illinois, have invented a new, original, and ornamental Design for a Combined Bridge and Mechanism Casing for Ice-Cream Freezers, of which the following is a specification, reference being had to the accompanying drawing, forming part thereof.

In the drawing, Figure 1 is a perspective view of a combined bridge and mechanism casing for ice-cream freezers, showing my new design.

Figure 2 is an enlarged plan view of the same.

I claim:

The ornamental design for a combined bridge and mechanism casing for ice-cream freezers, substantially as shown and described.

JAMES J. GOUGH.
